J. GRABOWSKI

THERMOSTATIC ALARM DEVICE

Filed Nov. 6. 1924

INVENTOR
John Grabowski
BY *John A. Peachy*
ATTORNEY

UNITED STATES PATENT OFFICE.

JOHN GRABOWSKI, OF PAWTUCKET, RHODE ISLAND.

THERMOSTATIC ALARM DEVICE.

Application filed November 8, 1924. Serial No. 748,024.

This invention relates to thermostatic alarm devices intended for use in buildings to give an alarm in the event of fire, or in the event of the temperature rising to a point threatening danger of fire.

The invention has for an object the provision of a simple and novel device of this type capable of ready adjustment as desired to operate at different temperatures.

For further comprehension of the invention, and of the objects and advantages thereof, reference will be had to the following description and accompanying drawing, and to the appended claims in which the various novel features of the invention are more particularly set forth.

Fig. 1 of the drawing is a face view of my improved thermostatic alarm device.

Fig. 2 is a side view thereof.

Fig. 3 is a fragmentary sectional view taken on the line 3—3 of Fig. 2.

My improved device as here shown comprises a board or panel 10 provided at one end with an aperture 11 whereby the device may be suspended from a desired part. Fixed to this board toward the lower end thereof, is a bracket 12 that projects therefrom and supports a shallow circular casing 13. The top of this casing is formed with a circular aperture with which the lower end of a vertical glass tube 14 registers, the glass tube being suitably fixed to the casing to form a tight joint. The bottom of the casing is in the form of a thin steel disk 15 that is annularly corrugated as shown to provide increased flexibility. Located under the casing, in axial alinement therewith, is a screw 16 that is threaded through a suitable aperture in the bracket 12 and is adapted to bear on the flexible bottom 15 of the casing to vary the capacity of the latter. This screw is formed with a head 17 on its lower end for purposes of rotation. Just above this head the screw is formed with a pair of vertically spaced radial flanges 18 between which projects one end of the horizontal arm of a bell crank lever 19 that is fulcrumed as at 20 to the board 10, the other arm of this lever being in the form of a needle or pointer 19' that extends upward and registers with a series of numbered marks 20 on the said board.

At its upper end the tube 14 is attached to the bottom of a small housing 23 of insulating material that is supported by a bracket 24 fixed to the board 10. Within this hous-

ing is mounted a vertically swingable arm 25 that is pivoted at one end to a head 26 on the inner end of a contact screw 27 fixed in the side of the housing, while the other end projects under the inner end of a second contact screw 28 fixed in the opposite side of the housing, this latter end of the arm normally resting on a stop element 29 fixed to the said housing. The lower casing 13 is filled with mercury that extends a distance up the tube 14. Located in the tube 14 is a cylindrical float 32 that rests in the mercury and has attached to its upper end an upwardly projecting rigid stem 33 that is aligned with the arm 25, so that when the float raises a sufficient distance in the tube the arm will be raised to close the circuit to an alarm element, or a series of alarm elements. As here shown a bell 35 is mounted on the board 10 under the casing 13, while an electric lamp 36 with a red bulb is mounted on the board above the top housing 23, these signal elements being connected in series with the contact screws 27, 28 and a battery 37, by wires indicated generally at 38, while other signal elements such as indicated at 39 may be placed outside the building, or in any desired remote locality.

As will be apparent, when the temperature of the surrounding air reaches a certain point the float 32 will be lifted by the mercury, to cause the stem 33 to bear on the arm 25 and raise the latter into engagement with the contact 28, thereby closing the circuit through the alarm elements. By rotating the screw 16 the capacity of the casing may be varied and the position of the top of the mercury in the tube for a given temperature varied, thereby varying the temperature at which the device will operate, the marks with which the pointers 19' registers being arranged to indicate the operating temperature for any given adjustment of the screw 16.

Having thus described my invention, what I claim as new and desire to protect by Letters Patent of the United States is as follows:

1. In a device of the class described, a mercury-filled receptacle having a flexible bottom member to vary its capacity, a float supported by the mercury in said receptacle, and aligned to close a switch upon the heating, and expanding of said mercury, an adjusting screw bearing on the said flexible bottom member to operate the same, and

- 2
- means connected to said screw to indicate the temperature at which the said float will close the said switch for each adjustment of the said screw, characterized by said screw being 5 provided near its head with vertically spaced radial flanges, between which projects one end of the horizontal arm of a bell crank that is fulcrumed to a board, the other arm of this crank being in the form 10 of a pointer that extends upwards, and registers with an indicating scale on the said board.
2. The combination in a device of the class described provided with an adjusting screw 15 bearing on the flexible bottom member of a mercury-filled receptacle, with a float supported by the mercury, and aligned to close a switch upon the expanding, by heating, of said mercury, of vertically spaced radial 20 flanges integral with said adjusting screw, a bell crank lever fulcrumed to a board, having its horizontal arm projecting between said flanges, and its other arm in the form
- of a pointer extending upwards, and registering with an indicating scale on the said 25 board.
3. The combination in a device of the class described provided with an adjusting screw bearing on the flexible bottom member of a mercury-filled receptacle, with a float supported by the mercury, and aligned to close 30 a switch upon the expanding, by heating, of said mercury, of vertically spaced radial flanges integral with said adjusting screw, a bell crank lever fulcrumed to a board, 35 having its horizontal arm projecting between said flanges for guidance, and its other arm in the form of a pointer extending upwards, and registering with an indicating scale on the said board to indicate the 40 temperature at which the float will close the said switch for each adjustment of the said screw.

In testimony whereof I have affixed my signature.

JOHN GRABOWSKI.
